UNITED STATES PATENT OFFICE.

PETER BEGHELLI, OF SAN FRANCISCO, CALIFORNIA.

WIRE TIGHTENER AND TWISTER.

Application filed March 9, 1925. Serial No. 14,010.

To all whom it may concern:

Be it known that I, PETER BEGHELLI, a citizen of the United States, residing at the city and county of San Francisco and State 5 of California, have invented new and useful Improvements in Wire Tighteners and Twisters, of which the following is a specification.

This invention relates to tighteners and 10 twisters for wires such as are used for tying forms together in the construction of concrete walls and the like.

In a prior application filed by me September 10, 1924, Serial Number 736,952, 15 now Patent No. 1,543,491 I show a clamp and tightener for similar purposes, and in the present invention I have modified the device so that the wires can be more conveniently tightened and thereafter twisted, 20 thus making it possible to immediately remove the tightener for use elsewhere.

One form which my invention may assume is exemplified in the following description and illustrated in the accompanying 25 drawing, in which

Fig. 1 shows a perspective view of a set of forms, showing my device applied to the tie wires, in position for tightening the same;

30 Figure 2 shows a similar view with the device of the present invention in position for twisting the wires;

Fig. 3 shows an end elevation of the device;

35 Fig. 4 shows a plan view of the same;

Fig. 5 shows a side elevation.

In its present form the tightener and 40 twister comprises a tapered or wedge-like plate 10 having a heel portion 11 extending at right angles thereto on the widened end. Fitted slidably upon this tapered or wedge-like plate is a clamping loop or band 12. At the narrow end of the plate 10 is an opening to slidably receive a rod or bar 13.

45 The device may be used in connection with forms such as indicated at 14, which are tied together by looped wires 15.

In the operation of the device, the ends 50 of the tie-wires are passed between the loop 12 and the plate 10, the said loop being retracted so as to permit the wires to be easily inserted therein. The device is placed against the form with the heel portion 11 resting against a rigid portion of the form, 55 and the clamping loop 12 is moved for-

wardly or towards the widened end of the plate 10, so as to engage the wire ends. The operator then pulls outwardly on the rod 13 as indicated in Fig. 1, which will cause the clamping loop 12 to tightly engage the 60 wires, and the said clamping loop and plate 10 will be pried outwardly with the end of the heel portion 11 acting as a fulcrum. When the wire is sufficiently tightened (which may require one or more operations 65 of the device) the said device is then rotated so as to twist the wire ends as indicated in Fig. 2. After the wire ends are sufficiently twisted, the device can be removed and other wires tightened and twisted 70 el in a similar manner.

The rod 13 may be arranged in any desired manner upon the plate 10, but it is preferable to have it slidably mounted thereon and provided with enlarged ends 16, so as to prevent removal or loss of the parts. By so slidably mounting the rod it can be shifted endwise to clear any obstructions 75 that may be in the way of the operator.

Various changes in the construction and 80 arrangement of the several parts herein shown and described may be employed without departing from the spirit of my invention, as disclosed in the appended claims.

What I claim as new and desire to secure 85 by Letters Patent is:

1. The combination with a form for concrete walls of the character indicated, and looped wires for aligning the forms and preventing spreading thereof, of a wedge-like plate having a heel portion formed at one end thereof to rest against the form, a clamping member slidably mounted on the wedge-like plate to engage the ends of the looped wire, and means in connection with 90 said wedge-like plate for prying the same outwardly, with the heel portion as a fulcrum, said means also enabling the operator to turn the plate whereby to twist the ends 95 of the wire.

2. The combination with a form for concrete walls of the character indicated, and a looped wire for aligning the forms and preventing spreading thereof, of a wedge-like plate having a heel portion formed at the enlarged end thereof and extending at right angles thereto, and adapted to rest against the form, a clamping member slidably mounted on the wedge-like plate to engage the ends of the wire, and a rod slid- 105 110

ably mounted on the outer end of said plate, forming a lever whereby the plate may be pried outwardly with the heel as a fulcrum, so as to tighten the wire and may likewise be turned so as to twist the wire after the same is tightened.

3. A tightener and twister for the purpose stated, comprising a wedge-like plate, a clamping ring slideable on the plate, a heel portion on the widened end of the plate, and means on the opposite end of the

plate forming a lever whereby to tilt the plate or turn the same.

4. A tightener and twister for the purpose stated, comprising a wedge-like plate, 15 a clamping ring slideable on the plate, a heel portion on the widened end of the plate, and a rod slidably mounted on the opposite end of the plate, forming a lever for tilting the plate or turning the same.

PETER BEGHELLI.
